UNITED STATES PATENT OFFICE.

PHILIP CAMELLI, OF WILMINGTON, DELAWARE.

ADJUSTABLE SWITCH-POINT RAIL SECTION.

Application filed April 22, 1922. Serial No. 556,043.

To all whom it may concern:

Be it known that I, PHILIP CAMELLI, a citizen of the United States of America, residing at Wilmington, in the county of 5 New Castle and State of Delaware, have invented certain new and useful Improvements in Adjustable Switch-Point Rail Sections, of which the following is a specification.

10 The present invention relates to improvements in adjustable switch point rail sections wherein the free ends of the switch points are forced into intimate engagement with a supporting tie to eliminate vibratory movement thereof in the passage of wheels of 15 rolling stock over the point.

The invention has particular reference to improvements over the different constructions of adjustable switch point rail sections 20 shown and described in patent granted to me June 22nd, 1920, Number 1,344,259, and patent granted March 29, 1921, Number 1,372,935, these patents referring in detail to tie bar No. 1 that is connected to the switch 25 point adjacent the swinging ends thereof. A depending offset extension is carried by each end of the tie bar No. 1 and underlies the base of the adjacent rail while a vertically adjustable plate is mounted on the tie bar 30 extension and is adjustable by screw bolts threaded through the tie bar extensions to cause the plate to engage the base of the rail with a consequent lowering movement of the tie bar and switch point carried thereby to 35 cause the switch point to lie in intimate contact with the supporting tie.

The present invention eliminates the manually operable screw bolt associated with tie bar No. 1 of the rails for adjusting the switch 40 points, and in lieu thereof provides automatically operating means in the form of spring devices for holding the switch points properly positioned upon the tie, the switch points being initially adjusted and there- 45 after automatically kept adjusted to a proper position relative to the tie to cause a substantially frictional engagement between the switch points and tie.

With the above general objects in view the 50 invention consists of the novel combination and arrangement of parts hereinafter more fully described in connection with accompanying drawings, and in which like reference characters designate corresponding 55 parts throughout the several views.

In the drawings:

Figure 1 is a top plan view of a portion of a railway track constructed in accordance with the present invention, showing tie bar No. 1 connected to the switch points, 60

Figure 2 is a cross sectional view of the track, showing the angle ends of tie bar No. 1 disposed beneath the track rails, the switch points carried by tie bar No. 1 and the spring devices interposed between the tie 65 bar extensions and the rails,

Figure 3 is a fragmentary side elevational view, partly in section of one end of tie bar No. 1 showing the depending angle offset extension carried by the end of the tie 70 bar and the spring devices interposed between the tie bar extension and the rail engaging plate.

Figure 4 is a perspective view of the rail engaging plate showing the counter-sunk 75 openings therein for the heads of the guide bolts, and

Figure 5 is a fragmentary perspective view of one end of tie bar No. 1 with the openings 80 therein for the passage of the guide bolts.

In the accompanying drawing, showing the preferred embodiment of the invention, the reference numeral 1 designates a cross tie of usual construction supporting rails 2 with which adjustable switch points 3 are 85 associated. Tie bar No. 1, designated by the reference numeral 4 is connected to the switch point 3 adjacent the swinging ends thereof. As shown in Figure 1 the tie bar carries a laterally extending socket 5 to 90 which a switch arm 6 is attached for throwing the switch points in the desired direction.

The tie bar No. 1 carries upon each end thereof depending offset extensions 7 provided with spaced openings 8 and is disposed beneath the rail 2 as shown in Figures 2 and 3, the same being materially spaced from the rails for purposes presently to appear. The points 3 are secured to tie bar No. 1 by the angle braces 9 adjacent the offset end extensions and upon shifting movement of the tie bar are selectively positioned into engagement with a rail as shown in Figure 2. 95

In the absence of devices for frictionally holding the switch points on the tie No. 1, the same will vibrate during passage of rolling stock thereover, resulting in damage thereto and rendering the points inoper- 110

ative. The present invention residing in the provision of means automatically operable for maintaining frictional engagement between the switch points 3 and the tie 1, 5 includes a plate 10 having spaced bolt receiving openings 11 registering with the bolt receiving openings 8 in the tie bar extension with the upper ends of the openings 11 counter-sunk as at 12, and being of polygonal formation for the reception of a similarly formed bolt head and preventing rotary movement of the bolt when positioned therein. As shown in Figure 3, the bolt 13 provided with a polygonal head 14 and a 10 threaded lower end 15 is positioned in the plate opening 11 with the head 14 received in the counter-sunk portion 12 of the opening 11, the lower threaded end 15 of the bolt freely passing through the opening 8 in the tie bar extension. The rail engaging plate 10 is positioned, above the tie bar extension 7 and spaced therefrom, the bolt 13 depending from the plate 10 and freely passing through the openings 8 in the tie bar extension, nuts 16 being threaded upon the 15 lower ends of the bolt beneath the tie bar extension while cotter pins 17 are selectively positioned in transverse openings 18 formed in the threaded end of the bolt to prevent accidental displacement of the nut 16. A coil spring 19 surrounds each bolt 13 and engages at its opposite ends the rail engaging plate 10 and the tie bar extension 7, normally holding the parts separated. 20

35 In the setting and operation of the device, the nuts 16 and cotter pins 17 being removed from the screw bolts 13, the springs 19 will cause a separating movement of the rail engaging plates 10 and the tie bar extensions 7, 25 the plate 10 being moved by the springs into engagement with the rail, while the tie bar and extension 7 are lowered relative to the rail, this latter movement being limited by the switch points 3 secured to the tie bar 30 intermediate the ends thereof as shown in Figure 2 by engagement with the tie 1. In adjusting the device and regulating the frictional engagement between the switch points and the tie, the nuts 16 are threaded onto 35 the lower ends of the bolts 13 for engagement with the lower face of the tie bar extension 7 compressing the springs 19 and regulating the extent of frictional engagement between the switch points and the tie, 40 and when so positioned, the cotters 17 are inserted in the desired opening 18 of the bolt to prevent the displacement of the nut 16 from the bolt. The device is entirely automatic in operation, after having been 45 initially set, the springs 19 forcing the plate 10 upwardly into engagement with base of the rail 2 will cause a lowering movement of tie bar No. 1 by the springs 19 engaging the tie bar extensions 7, thereby frictionally 50 holding the switch points into engagement

with the supporting tie to prevent rattling or vibrating movement thereof during the passage of rolling stock thereover.

Having thus described the invention, what I claim as new is:—

1. In combination, a pair of switch point rail sections, and a tie bar connecting the same, the tie bar being resiliently mounted to cause the switch point rail section to intimately contact the supporting ties. 70

2. In combination, a rail-way rail, a switch point rail section associated therewith, a tie bar carried by the switch point rail section and resiliently associated with the rail to automatically cause the switch point rail section to frictionally engage the supporting tie. 75

3. In combination, a rail-way rail, a switch point rail section associated therewith, a tie bar carried by the switch point rail section and extending beneath the rail-way rail, and resilient devices interposed between the rail-way rail and tie bar for causing a downward movement of the switch point rail section. 80

4. In combination, a rail-way rail, a switch point rail section associated therewith, a tie bar carried by the switch point rail section, a plate carried by the tie bar and arranged between the tie bar and rail-way rail and cushion devices interposed between the plate and tie bar whereby the switch point rail section is lowered onto the supporting tie. 90

5. In combination, a pair of switch point rail sections, a tie bar supporting the same, rail engaging members associated with the tie bar and cushion springs interposed between the tie bar and rail engaging members to cause the switch point frictionally 100 to engage the supporting tie. 100

6. In combination, a pair of switch point rail sections, a tie bar connecting the same, a rail engaging member associated with each end of the tie bar, a bolt carried by the rail 110 engaging member freely extending through the adjacent end of the tie bar and a coil spring surrounding the bolt between the rail engaging member and tie bar for frictionally holding the switch point in engagement with 115 a supporting tie.

7. In combination, a pair of switch point rail sections, a tie bar connecting the same, a rail engaging plate associated with each end of the tie bar, screw bolts carried by the rail 120 engaging plates freely extending through the tie bar coil springs surrounding the bolts between the rail engaging plates and the tie bar and a nut threaded on each bolt into engagement with the tie bar regulating the 125 extent of frictional engagement between the switch points and the supporting tie.

In testimony whereof I affix my signature.

PHILIP CAMELI.
